UNITED STATES PATENT OFFICE

FLOYD L. SCOTT, OF HOUSTON, TEXAS, ASSIGNOR TO HUGHES TOOL COMPANY, OF
HOUSTON, TEXAS, A CORPORATION OF TEXAS

CORE CATCHER

Application filed January 8, 1929. Serial No. 331,034.

My invention relates to means for engaging the core obtained in drilling with core drills.

It is an object of the invention to provide a simple construction of core catcher which is not liable to become clogged in use and therefore fail to function properly.

It is an object to construct the core engaging fingers so that the material cut by the drill may not get into the space behind the said fingers and interfere with their working properly.

Referring to the drawings, Fig. 1 is a central longitudinal section through a drill, having my invention employed thereon. Fig. 2 is a vertical section through the core catcher removed from the drill, taken on the plane 2-2 of Fig. 3.

Fig. 3 is a transverse section taken on the plane 3-3 of Fig. 2.

The core catcher may be employed with any ordinary type of core drill. I have shown it as used with a drill having a head divided into upper and lower sections. The upper section 1 is threaded to engage a drill collar at 2, and is also threaded to receive the core barrel bushing 3, in which the core barrel 4 is welded.

The lower section, or cutter head 5 shoulders against the upper section at 6, and has threaded engagement therewith at 7. The cutter head 5 has cutter blades 8 thereon to cut the bottom of the annular hole. It has passages 9 for flushing fluid which connect with an annular groove 10 in the shoulder 6. The channels 11 in the upper section 1 of the head connect the groove 10 with the passage through the drill collar above.

The cutter blades 8 extend into the central channel in the head a short distance at 12 so as to cut a core 13 slightly smaller than the central opening 14 in the head. The inner opening through the head is recessed at 15 to receive the core catcher 16. The said recess is deeper at its upper end and is tapered downwardly to form the converging seat 17. At the lower end of the seat, the recess is cylindrical to receive the sleeve 18 of the core catcher. The lower end of the

recess is formed with a supporting shoulder 19.

The core catcher body is made up of the sleeve 18 of heavy sheet metal. It has a plurality of slotted openings 20 in the sides through which may project the core engaging fingers 21. Below the slots 20, the outer wall of the sleeve is grooved at 22 to receive the lower ends of the said spring fingers, 21.

Said fingers are made up of strips of spring steel bent inwardly from their lower ends to cause the upper ends to project into the path of the core. The said upper ends are also bent or twisted slightly transversely so that one corner of each upper end is presented further inwardly than is the other, the said corner shown at 23 being on the receding side as the drill is rotated.

To prevent accumulations of material behind said fingers, blocks 24 of metal are secured to the outer sides of the spring fingers. Said blocks are wedge shaped, and when in place, serve to practically fill the openings 20 even when the fingers are bent inwardly. Thus, as seen from Fig. 2, the detritus from the drill cannot be forced in past the fingers and fill the recess 15 behind them, and prevent their moving out of the way of the core.

In Fig. 1 I have shown the position of the fingers when the core has moved past the fingers and it is to be noted that the recess 15 is filled by the blocks 24 upon the fingers so that no fragments of hard material from the core or the bottom of the hole can get past the fingers to clog their action. When the drill progresses, the core moves the fingers back, but when the core has been cut sufficiently, the upward movement of the drill and the core catcher, will cause the fingers to engage deeply into the core and break it off and serve to raise said core with said core catcher to the surface.

The advantage of this construction lies in the fact that the device will not clog in use but will function positively for prolonged periods. The arms 21 are strengthened by the blocks 24 and are also rendered free of accumulations of rock chips or fragments behind them which would interfere with ac-

100

Also, the arms 21 are strengthened by the blocks 24 which bear against the walls of the openings 20 as the drill is rotated thus preventing undue strain on the spring arms. The outer face being inclined outwardly at its forward edge, as seen in Fig. 3, the ends of the arms are forced past the core without great wear.

What I claim as new is:

- 10 1. A core catcher for core drills comprising a sleeve of metal shaped to fit within a core drill head, said sleeve having spaced openings therein, spring fingers secured at the lower ends of said openings and projecting inwardly at their upper ends, and means on said fingers to close said openings and prevent the entrance of material tending to clog action of said fingers.
- 15 2. A core catcher for core drills comprising a sleeve of metal shaped to fit within a core drill head, said sleeve having spaced longitudinal openings therein, spring fingers secured at the lower ends of said openings and projecting inwardly at their upper ends, and wedge shaped blocks secured to said fingers to close said openings and prevent the entrance of material tending to clog the action of said fingers.
- 20 3. A core catcher for core drills comprising a cylindrical sleeve, having spaced longitudinal openings therein, core engaging fingers secured to said sleeve and movable in said openings, and means on the outer faces of said fingers tending to fill said openings and prevent the passage of detritus.

In testimony whereof I hereunto affix my signature this 2nd day of January, A. D. 1929.

FLOYD L. SCOTT.
